UNITED STATES PATENT OFFICE.

ODES J. KENYON, OF SANTA BARBARA, CALIFORNIA, ASSIGNOR, BY MESNE ASSIGNMENTS, TO INSTANT ICE CORPORATION, A CORPORATION OF DELAWARE.

OIL SEPARATOR.

Application filed July 25, 1927. Serial No. 268,377.

The invention relates to pump constructions and finds particular utility in compressors for use in connection with refrigerating apparatus.

5 An important object of the present invention is to provide an oil separator arranged within the piston and designed to efficiently provide for the segregation or separation of the refrigerant from the oil prior to its entrance into the cylinder above the piston.

The invention has also among its objects to simplify, render more efficient, and improve generally devices of this character, and these as well as other objects, advantages and novel 15 details of construction will be made more apparent as this description proceeds, especially when considered in connection with the accompanying drawings, wherein,

Figure 1 is a sectional view through the 20 cylinder and piston of a compressor embodying my invention;

Figure 2 is an enlarged sectional view taken on the line 2—2 of Figure 1, and

Figure 3 is a sectional view taken substantially on the line 3—3 of Figure 1.

In the drawings wherein like reference characters indicate like parts, it will be noted that a portion of the compressor is illustrated at 10 comprising a cylinder 11 within which 30 a hollow piston 12 is reciprocably mounted.

In practice, a certain per cent of the lubricant contained in the crank case (not shown) of the compressor becomes mixed or intermingles with the refrigerating medium and is 35 pumped by the compressor through the refrigerating system. This action is objectionable as the oil will accumulate in the system, and particularly in the expansion coil and become viscous, which impedes the passage 40 of the gas and reduces the efficiency of the device.

In accordance with the present invention, however, the refrigerant containing a certain per cent of the lubricant passing into the hollow piston upon the suction stroke of the latter is separated from the lubricant. For accomplishing this result an oil separating chamber 13 is inserted within the upper portion 45 of the hollow piston. As shown this chamber is preferably cylindrical and is formed with a substantially flat bottom 14 and an inverted cone shaped top 15 having the central opening 16. In order to permit the gas to pass upwardly into the chamber 13 50 the bottom 14 thereof is formed with a se-

ries of apertures 17. As shown these apertures are spaced a considerable distance from the outer wall of the chamber and are punched in such a manner as to make the openings point tangentially towards the side 60 walls of the chamber, as clearly shown in Figure 2. With such an arrangement the gas containing the lubricant upon passing through the apertures 17 will have a tendency 65 to flow in the direction indicated by the arrow in Figure 2 causing a centrifugal action in the chamber 13 tending to separate the oil from the refrigerant. This action is accentuated because of the greater specific gravity 70 of the oil, which upon entering the chamber 75 13 is not sufficiently suspended by the refrigerant to be drawn upwardly and through the central opening 16, but on the other hand falls in the chamber 13 and flows through ports 18 formed in the bottom 14 of the chamber adjacent the side walls thereof. The downwardly inclined walls of the inverted conical top 15 cooperate with the side walls 80 of the chamber to form a pocket for arresting the gas prior to its escape through the central 85 aperture 16, thereby insuring a complete separation between the gas and lubricant.

For efficiently holding the oil separating chamber 13 in the top portion of the piston, a wrist pin bearing 19 is provided. As shown 90 this bearing threadedly engages the skirt of the piston and is formed with a circumferentially extending seat portion 20 at the top thereof engageable with the bottom wall of the chamber. The top of the bearing is further formed with an inverted conical portion 21 the inner edge of which extends inwardly to a point beyond the oil outlet ports 18. With such an arrangement the conical portion 21 not only functions as an efficient 95 guide for the oil passing through the ports 18, but also curtails or restricts the gas from flowing up through the ports 18.

In order to permit the gas flowing upwardly through the central aperture 16 to enter 100 the cylinder above the piston, the head of the latter is formed with a plurality of valve controlled ports 22. The valve may be of any suitable construction, opening as the piston descends to permit the gas to flow into 105 the cylinder and closing as the piston rises to allow the gas to be compressed in the cylinder.

In use, as the piston descends the refrigerant mixed more or less with the lubricant, 110

will pass up from the crank case of the compressor through the ports 17 and, due to the particular configuration of these ports, will be directed towards the side walls of the separating chamber 13, wherein the oil is separated from the refrigerant in a manner heretofore set forth. The refrigerant then passes up through the central aperture 16 and ports 22 into the cylinder. The oil on the other hand flows through the ports 18 upon the inclined wall 21 and into the crank case. In this connection it is to be noted that, if for any reason the gas is expelled from the oil separating chamber before the lubricant has been entirely separated therefrom, this lubricant is invariably separated from the gas on its ascent to the ports 22. The lubricant falls upon and is collected by the downwardly inclined walls of the inverted cone top 15 of the chamber 13 and flows back through the aperture 16 into the chamber 13. Thus it will be apparent that the top wall of the chamber 13 cooperates with the head of the piston to form a second arresting chamber.

What I claim as my invention:

1. In a compressor, the combination with a reciprocatory hollow piston, of a lubricant arresting chamber arranged within and detachably secured to said piston.

2. In a compressor, the combination with a reciprocatory hollow piston, of a substantially cylindrical lubricant arresting chamber sleeved within said piston.

3. In a compressor, the combination with a reciprocatory piston having a series of openings in the top portion thereof for the flow of refrigerant, of a hollow lubricant arresting chamber arranged within said piston directly beneath said openings and having an opening communicating with the openings in said piston.

4. In a compressor, the combination with a reciprocatory piston, of a lubricant arresting chamber associated with said piston having a bottom wall formed with a plurality of spirally inclined ports for the flow of refrigerant.

5. In a compressor, the combination with a reciprocatory piston having a series of openings for the flow of refrigerant, of a lubricant arresting chamber arranged within said piston having an aperture communicating with the openings aforesaid and having a plurality of spirally inclined ports in the bottom wall thereof.

6. In a compressor, the combination with a reciprocatory hollow piston, of a lubricant arresting chamber removably secured within said piston.

7. In a compressor, the combination with a reciprocatory piston therein, and a lubricant arresting chamber associated with said piston having a bottom formed with a plurality of spirally inclined ports for the flow

of refrigerant and also formed with a plurality of passages spaced outwardly from the ports for the flow of the lubricant.

8. In a compressor, the combination with a reciprocatory hollow piston having a series of valve controlled openings for the flow of refrigerant, of a cylindrical lubricant arresting chamber arranged within the upper portion of the piston having a bottom formed with a plurality of openings constituting the inlet ports for the refrigerant and oil and having an inverted cone-shaped top formed with a central aperture constituting the outlet passage for the refrigerant.

9. In a compressor, the combination with a reciprocatory hollow piston having an opening therein for the flow of refrigerant, of a lubricant arresting chamber arranged within said piston having a diameter substantially equal to the interior diameter of the piston, said chamber being formed with an inverted cone-shaped top apertured to establish communication between the chamber and openings aforesaid.

10. In a compressor, the combination with a reciprocatory hollow piston, a lubricant arresting chamber arranged within said piston, of means for securing said chamber in said piston including a member threadedly engaging said piston.

11. In a compressor, the combination with a reciprocatory hollow piston, of a lubricant arresting chamber arranged within said piston, and means for securing said chamber in said piston including a wrist pin bearing detachably engaging said piston and having a portion abutting the bottom of said chamber.

12. In a compressor, the combination with a reciprocatory hollow piston, of a lubricant arresting chamber arranged within said piston having a plurality of spirally inclined ports for the flow of refrigerant and having a plurality of passages spaced outwardly from the ports aforesaid constituting outlet passages for the lubricant, and a wrist pin bearing threadedly engaging the piston having a portion abutting the bottom of said chamber to hold the same in place and having an inverted conical portion projecting inwardly past the passages aforesaid for collecting the lubricant flowing therethrough and for preventing the refrigerant from passing upwardly through the passages.

13. In a compressor, the combination with a reciprocatory hollow piston, of a lubricant arresting chamber arranged within said piston having an inverted cone-shaped top cooperating with the inner surface of the piston head to form a second lubricant arresting chamber.

14. In a compressor, the combination with a piston, of a lubricant arresting chamber arranged within said piston and adapted to receive a fluid, said chamber having means for effecting a whirling action of the fluid

upon the entrance of the latter in said chamber.

15. In a compressor, the combination with a piston having a wrist pin bearing, of a lubricant arresting chamber arranged within 5 said piston and held in place by said wrist pin bearing.

16. In a compressor, the combination with a piston, of a lubricant arresting chamber disposed within said piston and having substantially cylindrical side walls bearing against 10 the inner walls of said piston.

17. In a compressor, the combination with a piston, of a lubricant arresting chamber arranged within said piston having a depressed 15 apertured top wall cooperating with the head of said piston to form a second arresting chamber.

18. In a compressor, the combination with 20 a piston having a wrist pin bearing, of a lubricant arresting chamber clamped between

said wrist pin bearing and head of said piston.

19. In combination, a piston having a ported head and a depending skirt, means in the skirt for directing a mixture of fluids toward 25 the side walls of said skirt, and means above the means aforesaid for arresting one of said fluids while permitting another of said fluids to flow to said ported head.

20. In combination, a piston having a ported head and a depending skirt, a chamber within the skirt having means in its bottom wall for directing a mixture of fluids toward the side walls of said chamber so that one of 30 said fluids will be arrested, having means in 35 the top wall for permitting another of said fluids to flow to said ported head, and having other means in its bottom wall for permitting the escape of the arrested fluid.

In testimony whereof I affix my signature.

OADES J. KENYON.
